(57) **CLAIM**

The ornamental design for a brushcutter, as shown and described.

DESCRIPTION

FIG. 1A is the first portion of a perspective view of a brushcutter of the present invention;

FIG. 1B is the second portion of a perspective view of a brushcutter of the present invention.

FIG. 2A is the first portion of a top view of the brushcutter of FIG. 1;

FIG. 2B is the second portion of a top view of the brushcutter of FIG. 1;

FIG. 3A is the first portion of a bottom view of the brushcutter of FIG. 1;

FIG. 3B is the second portion of a bottom view of the brushcutter of FIG. 1;

FIG. 4A is the first portion of a right side view of the brushcutter of FIG. 1;

FIG. 4B is the second portion of a right side view of the brushcutter of FIG. 1;

FIG. 5A is the first portion of a left side view of the brushcutter of FIG. 1;

FIG. 5B is the second portion of a left side view of the brushcutter of FIG. 1;

FIG. 6 is a rear view of the brushcutter of FIG. 1; and,

FIG. 7 is a front view of the brushcutter of FIG. 1.

The broken lines in the drawings illustrate portions of the brushcutter and form no part of the claimed design.

1 Claim, 8 Drawing Sheets
